Primary Examiner — Jonathan J Han*Assistant Examiner* — Molly K. Orzechowski(74) *Attorney, Agent, or Firm* — ScienBiziP, P.C.(57) **CLAIM**

The ornamental design for a slipper as shown and described.

DESCRIPTION

FIG. 1 is a front, top, and right side perspective view of a slipper, showing my design.

FIG. 2 is a rear, bottom, and left side perspective view thereof.

FIG. 3 is a right side view thereof.

FIG. 4 is a left side view thereof.

FIG. 5 is a front view thereof.

FIG. 6 is a rear view thereof.

FIG. 7 is a top view thereof.

FIG. 8 is a bottom view thereof; and,

FIG. 9 is an exploded view thereof.

A slipper for the left foot is a mirror image of the slipper for the right foot as shown in FIGS. 1 to 9 and is also claimed.

1 Claim, 9 Drawing Sheets(56)
